COUCH-BED.

1,119,053.

Specification of Letters Patent.

Patented Dec. 1, 1914.

Application filed January 29, 1909. Serial No. 474,901.

To all whom it may concern:

Be it known that I, GEORGE H. ST. CLAIR, of Lynn, in the county of Essex and State of Massachusetts, have invented certain new and useful Improvements in Couch-Beds, of which the following is a specification.

This invention has relation to convertible couch beds, and has for its object to provide certain improvements therein by which the sections may be shifted or moved relatively to each other with greater ease than heretofore, by which the mattress fabrics may be brought more nearly into the same horizontal plane, and by which the sections may be more effectively nested than heretofore.

In carrying out the invention, I provide two couch sections of which the lower section is complete, with the usual four legs or supports, and an upper movable section which may be caused to overlie the first-mentioned section or else to be projected laterally to one side so as to overlap only the side of the first-mentioned section, the said upper section having legs or supports on only one side and having its other side supported on the lower section.

The two sections are connected together by pivoted connections, so that their relative movement is limited, and they are caused to assume either one of only two different positions with respect to each other. The said connections are so formed that when the upper section is shifted laterally, its inner side is lifted bodily so as to free it from engagement with the lower section, and it is held up until said section reaches the limit of its outward lateral movement when said inner side is dropped so as to rest upon the lower section. The connections between the said sections are so formed and are provided with treadles that by actuating the said connections, the upper section may be moved laterally one way or the other with very little exertion. The said connections include a rod or shaft which is located beneath the mattress fabric of the lower section, arms at the ends thereof which connect said shaft with the inner side of the upper section, and supports on which said rod or shaft is mounted. The supports at each end of the lower section consist of crossed links, pivoted at the lower ends to the lower section and the upper ends to lateral projections on said arms, so that the said shaft is

partially rotated and at the same time is moved through a substantially parabolic curve, in consequence of which the upper section is not lifted unduly when it is shifted as it would be were the arms movable about a fixed axis and of the necessary length.

Referring to the accompanying drawings, Figure 1 represents in end elevation my improved couch bed with the sections nested. Fig. 2 represents a longitudinal section on the line 2—2 of Fig. 1. Figs. 3 and 4 represent end elevations respectively showing the movable section projected half-way and fully projected.

Referring to the drawings, the couch bed therein illustrated comprises two sections which I may term the upper and lower sections or the movable and stationary sections, and are indicated respectively at A and B. The lower or stationary section consists of end frames which are connected by side bars 10. The end frames are illustrated as having legs or supports 11, 11 connected at their upper ends by cross-bars 12, and at or near their lower ends by cross-bars 13. The uprights 11 and the cross-bars 12 are preferably, though not necessarily, made of angle bars suitably riveted or otherwise connected together. Stretched between the horizontal webs of the cross-bars 12 is any suitable mattress fabric indicated as a whole at 14. This fabric or "spring mattress" is illustrated as being of the "National" type, but it will be understood that any suitable fabric may be utilized in lieu of the one shown. In the lower end of each of the legs or supports 12 is secured a tri-lateral caster bracket 15, in the horizontal web of which is mounted a caster 16. It will be understood that, although I have described this section of the couch bed in detail, nevertheless said section may be made in any other convenient way that may suggest itself to the manufacturer.

The upper or movable section B consists of end cross-bars 17 between which is stretched the mattress fabric 18, said end bars being illustrated as angle bars so that their horizontal webs may rest upon the horizontal webs of the end bars 12, and their vertical webs lie outside the vertical webs of said cross-bars 12 of the lower or stationary section. At their outer ends, the end bars 17 are attached in any suitable way to legs or uprights 19, the

latter being connected together by side bars 20 (see dotted lines Figs. 3 and 4). The posts or uprights 19 are illustrated as tubular or cylindrical and they are carried above the plane of the mattress 18, and are curved inwardly and then downwardly so as to constitute head and foot pieces 21, 21, their inner ends being secured by any suitable means to the inner ends of the end bars 17. 5 By virtue of this construction, the parts being of the proper length and width, it will be seen that the movable or upper section 17 may be caused to overlap the lower or stationary section, as shown in Fig. 1, 10 with the mattress 18 completely overlapping the mattress 14 and with the end bars 17 resting upon the end bars 12. With the two sections thus nested together the structure may be used as a couch or single bed. By 15 moving the upper or movable frame laterally or outwardly into the position shown in Fig. 4, the couch may be made into a double bed. The inner ends of the end bars 17 then rest upon the lower section, the outer ends 20 of said cross-bars being supported by the legs or supports 19. In order to limit the 25 relative movement of the two sections and also for the purpose of providing means for shifting them or moving one relatively 30 to the other, I provide the following mechanism.

22 is a rod or shaft which lies beneath the mattress of the lower section and which extends from end to end of the said section 35 as shown in Fig. 2. Rigidly secured to the ends of said rod or shaft are two arms 23 whose free ends are pivoted as at 24 to the inner ends of the end bars 17 of the movable section. The said rod or shaft and the two 40 arms 23 assist the side bars 20 in spacing the end bars 17 apart, and thus maintaining the mattress fabric 18 in a taut or stretched condition. Each of the arms 23 is provided or formed with two shorter divergent lugs 45 24^a 24^b, to the ends of which are pivoted two crossed links 25, 26 respectively, each of said arms with the associated lugs thus forming virtually a three armed lever. The said crossed links have their lower ends pivoted 50 at separate points to the cross-bar 13 at the ends of the lower section. The link 25 is on the inside of the vertical web of the cross-bar 13, whereas the link 26 is on the outer side of said web as shown in Figs. 2 and 3. 55 The arms 23, lugs 24^a and 24^b and the links 25, 26 are of such length that, when the upper section is moved outwardly relatively to the lower section, the inner ends of the end bars 17 will rest upon the outer ends 60 of the cross-bars 12, and that, when the upper section is moved inwardly, the inner ends of the end bars 17 will register with the inner ends of the cross-bars 12, and the mattress fabric 18 lie immediately above the 65 fabric 14.

By reason of the crossed links 25, 26 and the lugs 24^a, 24^b the inner end of the upper section is raised and the upper section is shifted laterally to one side or the other so that the mattress frames and the mattress 70 of the two sections are completely disengaged as shown by Fig. 3. This is accomplished by the oscillation of the arms 23 and it will be noticed in this connection that not only are the shaft 22 and the arms 23 oscillated but that they are at the same time moved bodily through a curved path. The free ends of the arms 23 are caused to move through a path which is in the nature of a curve approximating the longer or flatter 75 side of an ellipse, in consequence of which the inner end of the upper section is not lifted as high as it would be were the arms 23 mounted upon a fixed axis and of sufficient length to give the required range of 80 movement to the movable section.

To provide for shifting the upper section, I attach to the two lugs 24^a, 24^b at one end of the bed treadles 28, 29. These treadles are divergent and are arranged substantially radial of the rod or shaft 22. At the end of each treadle is a foot piece 30 with which may be engaged the foot of the operator. If it be desired to move the upper frame laterally or outwardly from the position shown in Fig. 1, the operator has but to place his foot upon the foot piece 30 of the treadle 29 and to depress the same. By reason of the compound levers consisting of the lugs 24^a, 24^b, the links 25, 26 and the arms 23, it requires very little effort for the operator to move the upper section outwardly. When the sections are nested together, the treadle 29 is approximately horizontal and the treadle 28 depends almost 105 vertically, and when the upper section has been moved outwardly to the position shown in Fig. 4, the parts are reversed, the treadle 28 being approximately horizontal and the treadle 29 approximately vertical. 110

A construction such as herein described, possesses numerous advantages which will be apparent to those skilled in the art to which this invention relates, and it will furthermore be seen by such persons that the 115 invention is capable of a variety of embodiments which will readily suggest themselves. Consequently I do not wish to be limited to the particular embodiment of the invention which I have herein illustrated 120 and described in detail, and to that end it will be recognized that the terminology which I have adopted is for the purpose of description and not of limitation.

I claim:—

1. A convertible couch bed comprising a relatively stationary section, a relatively movable section having supports at one side to rest on a floor and adapted to overlap and rest on said relatively stationary sec- 130

tion at its other side, arms pivotally connected to the overlapping side of said relatively movable section, and movable supporting means mounted on said relatively 5 stationary section, to which said arms are pivotally connected.

2. A couch-bed comprising a relatively stationary, lower section, a relatively movable upper section adapted to overlie and 10 rest upon said lower section, being laterally movable, arms near each end of the bed pivoted to said upper section, and links pivotally connected to said arms and to said lower section by which said arms are supported, said arms and links serving to guide 15 the overlying edge of the upper section from one side to the other of the lower section in a path but slightly elevated above the lower section.

20 3. A convertible couch-bed consisting of a relatively stationary lower section, an upper section adapted to overlie said lower section and movable laterally relatively thereto so as to extend and diminish the width of 25 the bed, supports at one side of said upper section adapted to rest on the floor, a shaft extending longitudinally of the bed, arms extending from said shaft and pivotally united to the upper section adjacent its ends 30 and its overlying side, and swinging supports by which said shaft is connected to the lower section so that said shaft is oscillated and moved sidewise when the bed sections are relatively moved, and said arms are 35 caused to raise the overlying part of the upper section and guide the same in a path slightly elevated above the lower section.

4. A convertible couch-bed consisting of a relatively stationary lower section, an upper section adapted to overlie said lower section and movable laterally relatively thereto so as to extend and diminish the width of the bed, supports at one side of said upper section adapted to rest on the floor, a shaft 40 extending longitudinally of the bed, arms extending from said shaft and pivotally united to the upper section adjacent its ends and its overlying side, lugs extending divergently from said shaft, links pivoted to 45 the lower part of the lower section at separated points crossing each other and each pivotally connected to one of said lugs, whereby said shaft is caused to move laterally and to oscillate when the couch sections 50 are relatively moved, whereby the points of attachment between said arms and the upper section are caused to travel in a curved path having a less elevation than if the arms were caused to swing about a fixed axis.

60 5. A couch bed consisting of relatively stationary and movable sections, the latter being adapted to overlie the former and having at one side supports adapted to rest on the floor, a floating shaft parallel to the 65 longitudinal dimension of the bed, arms rig-

idly secured to said shaft and held thereby at an invariable distance apart, being pivotally connected to said movable section near the ends thereof and adjacent to the side opposite to that at which said supports 70 are connected, and movable supporting means for the shaft mounted on the relatively stationary section, with which the shaft is connected, with capability for relative oscillating movement.

75 6. A couch-bed consisting of a relatively stationary section which is self-supporting, a relatively movable section adapted to overlie said first section and to be placed with one of its side edges resting on a side of the first section, supports for the outer side of said relatively movable section adapted to rest on the floor, a three-armed lever connected pivotally to said relatively movable section near each end, and near that side 80 thereof which is supported by the first section, and links connected to the other two arms of said levers and to the frame of the first section, said links being crossed, whereby to give the levers swinging and translative movements when the sections are relatively moved.

90 7. A couch-bed consisting of a relatively stationary section which is self-supporting, a relatively movable section adapted to overlie said first section and to be placed with one of its side edges resting on a side of the first section, supports for the outer side of said relatively movable section adapted to rest on the floor, a three-armed lever having a long arm pivotally connected to the second section adjacent to the side thereof which rests upon the first section, and links pivoted to the other two arms of said lever and to the frame of the first said section, 95 said last arms having accessible portions whereby the lever may be swung so as to shift the movable section to widen or reduce the width of the bed.

100 8. A couch bed consisting of relatively stationary and movable sections, the latter being adapted to overlie the former and having at one side supports adapted to rest on the floor, a floating shaft parallel to the longitudinal dimension of the bed, arms rigidly secured to said shaft and held thereby at an invariable distance apart, being pivotally connected to said movable section near the ends thereof and adjacent to the side opposite to that at which said supports 115 are connected, and treadles, connected with said shaft and extending divergently therefrom.

120 9. A convertible bed-couch, comprising relatively movable and stationary sections, one of which is adapted to overlie the other and to be extended in continuation thereof, and means for moving the first said section relatively to the other, including arms pivotally connected to said movable 125 130

- section near its ends, and crossed links pivoted to the lower part of said stationary section and to separated points on said arms.
10. A convertible bed-couch, comprising relatively movable and stationary sections, one of which is adapted to overlie the other and to be extended in continuation thereof, and means for moving the movable section relatively to the stationary section comprising rigidly connected arms adjacent to the ends of the movable section pivotally connected to the latter, and a floating linkage connection between said arms and a portion of the stationary section.
- 15 11. A couch bed comprising a stationary section having supports and side- and cross-bars connecting said supports, a movable section adapted to overlie said stationary section and movable into a position at one side of and in extension of said section, said movable section having supports at its outer corners adapted to rest on the floor, a side bar connecting said supports, and end bars connected to said supports and parallel with the end bars of the stationary section, and means for shifting said movable section, consisting of arms pivotally supported by
- 30 said stationary section, and connected to the cross-bars of said movable section near the ends thereof opposite to the supports of such section, and a rod or shaft to which said arms are rigidly connected and by which the end bars of the movable section are spaced apart.
12. A couch bed comprising a relatively stationary section, a relatively movable section adapted to move laterally with respect to said relatively stationary section for widening and contracting the bed, and means for so moving the relatively movable section, including an arm connected with the relatively movable section, and means connecting said arm with the relatively stationary section in a manner permitting simultaneous oscillative and translatable movement of the arm bodily in the direction in which the relatively movable section moves.
- 35 In testimony whereof I have affixed my signature, in presence of two witnesses.
